UNITED STATES PATENT OFFICE.

TIMOTHY RYAN, OF CHICAGO, ILLINOIS.

MITTEN.

SPECIFICATION forming part of Letters Patent No. 243,728, dated July 5, 1881.

Application filed April 4, 1881. (No model.)

To all whom it may concern:

Be it known that I, TIMOTHY RYAN, of Chicago, in the county of Cook and State of Illinois, have invented certain new and useful 5 Improvements in Mittens, of which the following is a specification.

My present invention relates to that class of mittens which are made of wool-skin and provided with wristlets or cuffs of knit or flexible 10 material; and it consists in securing to the wristlets stays, of tape or similar goods, in such manner that the strain caused by pulling on the gloves will be received and sustained by the stays, thereby relieving the wristlet, preventing its being stretched needlessly, and 15 lengthening its life of usefulness.

In Figure 1 is shown a mitten or glove opened so as to expose the interior upon both sides; and Fig. 2 is a section of the same, taken 20 longitudinally through one of the stays.

In said drawings, A represents the body of a mitten, formed of sheep-skin having the wool 25 a upon it to give warmth, and B is the wristlet, made of knit fabric, so it will be elastic, to yield to the passage of the hand and close snugly upon the wrist, and possess at the same time a good degree of warmth. To save this wristlet from being stretched and injured in pulling on the mitten I provide it, at the point

where the wearer naturally takes hold in that 30 operation, with one or more stays, C, which extend from near the outer edge of the cuff up to and upon the body of the mitten, and secure it to both cuff and body by stitching, as shown at c. The wearer, in donning the mitten, takes 35 between his thumb and forefinger that portion of the cuff to which the stay is secured, and the strain is therefore put directly upon the latter; and, being made of tape or other non-elastic fabric, it transmits the force directly to 40 the body of the mitten. I prefer to apply these stays to both palm and back of the mitten, and there may be more than two of them, if desired, and they may be secured either to the inside or outside, as fancy may dictate. 45 These stays do not interfere with the stretch of the cuff crosswise, but they prevent its being drawn out of shape by pulling-strains in the other direction.

I claim—

The combination, with the mitten consisting of the wool-skin body A and flexible wristlet B, of the stay or stays C, substantially as and for the purpose set forth.

TIMOTHY RYAN.
